UNITED STATES PATENT OFFICE.

ROBERT L. SHORT, OF JANESVILLE, WISCONSIN, ASSIGNOR TO THE SPRINGFIELD MACHINE COMPANY, OF SPRINGFIELD, OHIO.

HAY ELEVATOR AND CARRIER.

SPECIFICATION forming part of Letters Patent No. 320,594, dated June 23, 1885.

Application filed November 5, 1884. (No model.)

To all whom it may concern:

Be it known that I, ROBERT L. SHORT, of Janesville, in the county of Rock and State of Wisconsin, have invented a new and useful Improvement in Hay Elevators and Carriers, of which the following is a full, clear, and exact description, reference being had to the accompanying drawings, making part of this specification.

10 My invention relates to an improvement in hay elevators and carriers, or, more specifically, to a sliding or traveling carriage and tackle by means of which hay, straw, or other suitable substance may be elevated from the ground or vehicle to a suitable track and carried along the same to any desired point, where it may be discharged.

15 My invention consists in the combination, with an elevated rail or track, of a suitable fixed gear-block or stops, and to the combination, with said track and gear-block, of a reversible traveling carriage, adapted by suitable wheels or rollers to travel along said track or rail and be engaged by and brought to a stop 25 when it reaches the gear-block, by means of a gear wheel or disk adapted to rotate within or between the side walls or casing of said carriage, said wheel or disk having a limited rotary movement, by means of which and other 30 details of arrangement and construction of parts the progress of the traveling carriage is checked, for a purpose hereinafter described.

35 My invention relates also to the peculiar construction of the gear wheel or disk, whereby the hay-forks and hay upheld thereby may be retained in their elevated position by the engagement of the hoisting-pulley or an arm thereon with the said gear wheel or disk while the carriage is moving along the rail.

40 In the accompanying drawings, Figure 1 represents a side elevation of my improved traveling carriage and pulley; Fig. 2, a similar view with one side of the carriage removed to show the arrangement of parts; Fig. 3, 45 a plan view of the same; and Figs. 4 and 5, detail views of a portion of the gear-wheels or disk and the vibrating locking-latch, respectively.

A represents a rail of suitable size, forming

the track upon which the carriage hereinafter 50 described is adapted to travel, for the purpose of carrying hay, straw, or other material from place to place. The device to be described may be used for elevating hay from the wagon to the roof of a barn or barrack, carrying the 55 same along until it reaches the desired point and discharging it on the mow; or it may be used as a hay-stacker in the field; or it may be used for elevating articles through windows, and in various ways that need not be 60 mentioned herein.

B and B' represent the side walls or casing of the carriage, which are substantially of the form shown in Figs. 1 and 3—that is, provided with upwardly extending and diverging 65 arms b b, which span the rail A, and are provided at or near their upper ends with rollers b' b', as shown, which rest and roll upon the upper face of the rail or track. These 70 rollers are located at sufficient distance apart to allow the attachment of the pendent rods necessary for sustaining the rail and withstanding any strain that may be brought thereon. The side walls or plates, B and B', of the carriage are connected by suitable bolts 75 or rivets, surrounded by elongated washers for holding said plates far enough apart to allow for the interposition of the gear-wheel or disk hereinabove referred to, and also for the introduction of suitable pulleys, levers, and 80 springs hereinafter specified.

C represents a disk formed of two flanged annular plates connected at their centers or in any suitable manner. The outer periphery of said disk is provided with cogs or teeth c c, 85 which correspond in form to and are adapted to be engaged by teeth or cogs c' c' on a fixed plate, C', secured to the under face of rail A.

D D represent the flanges formed upon the inner adjacent faces of the annular plates, together constituting the disk C. These flanges, when the two parts of the wheel are connected, are located, as to their adjacent edges, at such a distance apart as to allow the passage of a short arm, E, pivoted within the casing of the 95 carriage and provided upon its swinging end with a head or latch, d. This head or latch d is adapted to enter a corresponding recess or

slot, d' , made in the flanges D D, for locking the disk C and preventing its further rotation. For insuring the action of the lever E and latch or head d a spring, e, is employed, which 5 presses against the under side of the axle of disk C, and exerts its tension to force the latch d into one of the slots d' of said disk.

The hoisting-rope (designated by F) passes over suitable pulleys, F' and F'', within the casing of the carriage, being secured at one end around a pin, f, for that purpose. Immediately of these pulleys the rope is passed through a hoisting pulley-block, H, of any ordinary description, such as are in common 15 use, with this difference, viz: upon its upper face, and projecting upwardly therefrom, is a pin, h, having a head, h', corresponding to a recess in the lower face of the latch or head d of the lever E. The hay-tongs may be of any 20 desired pattern, and are supported by a hook, h'', projecting downwardly from the block H.

The operation of the device is as follows: The rope F being fast at one end, by pulling at the opposite end the effect will be to raise 25 the block H and force the head h' of pin h up against latch d , resting in the slot d' of the flanged disk C. As the block H continues its upward progress, it operates to lift the latch d out of engagement with slot d' , and as soon as 30 this is accomplished the wheel or disk C, being no longer locked by the latch d , is left free to rotate, and moves along the rail under the influence of the tension on the rope F. When the head h' of pin h has lifted the latch d 35 out of the recess d' , and the disk begins to revolve, the head h' is caught behind or above the flanges D D, and the block, together with its load, is sustained independently of the tension on the rope.

40 To prevent the wheel from rotating too far and thus releasing the head of the block through another of the slots d' , a locking-latch, I, provided with the catch I', is employed, said catch entering one of the slots d' 45 and preventing further rotation of the disk C. A weight, I'', upon the outer end of the latch-lever, serves to hold the catch in engagement.

One of the particular advantages of my improvement is that the hay-carrier shown and 50 described is reversible by simply securing the opposite end of the rope to the carriage and pulling in the reverse direction.

I am aware that a reversible carrier is not new; therefore I do not claim this feature, 55 broadly; but,

Having now described my invention, I claim as new--

1. In a hay elevator and carrier, the combination, with the supporting rail or track, of the toothed stop-plate secured thereto, and the carriage provided with the cogged disk, adapted to be engaged by the toothed stop-plate for stopping and holding the carriage. 60

2. In a hay elevator and carrier, the supporting rail or track, and the toothed stop-plate secured thereto, in combination with the carriage, adapted to travel on said rail or track, and provided with the cogged disk, and a pivoted latch for locking said disk against rotation. 65

3. In a hay elevator and carrier, the combination, with the rail or track provided with the toothed stop plate, of the carriage provided with the cogged disk, the pivoted latch for locking said disk against rotation, and the pin or head upon the elevator-block for operating said latch to release the cogged disk and the carrier. 70

4. The rail or track provided with the toothed stop-plate, and the carriage adapted to travel upon said rail and provided with the toothed disk, in combination with a pivoted latch adapted to engage a slot or notch in said disk, the pin on the elevator-block for operating said latch, and flanges on the disk for 85 engaging the head of the pin on the elevator-block, all substantially as described.

5. The combination of the rail or track, the toothed stop-plate secured thereto, the carriage adapted to travel upon said rail or track, 90 the toothed disk carried by said carriage, the pivoted latch for locking said disk, the pin or head on the elevator-block for operating said latch to release the disk, the flanges on the toothed disk for engaging the head on the elevator-block, and the secondary latch for locking the disk after it has been released from the stop-plate, substantially as described. 95

6. The combination, with the traveling carriage, of the toothed stop-plate and the cogged disk engaging therewith, the pivoted latch, the elevator-pulley, provided with a head or pin for operating said latch, and cord-pulleys, arranged, substantially as described, whereby the latch is adapted to be 105 operated by tension on the cord in either direction.

In testimony whereof I have hereunto set my hand this 17th day of September, A. D. 1884.

ROBERT L. SHORT.
